UNITED STATES PATENT OFFICE.

JAMES EVRET RACHIELLES, OF CHEROKEE, ALABAMA, ASSIGNOR OF ONE-HALF TO GEORGE E. BURBANK, OF SAME PLACE.

STONE-DRILLING MACHINE.

SPECIFICATION forming part of Letters Patent No. 531,967, dated January 1, 1895.

Application filed February 20, 1894. Serial No. 500,899. (No model.)

To all whom it may concern:

Be it known that I, JAMES EVRET RACHIELLES, of Cherokee, in the county of Colbert and State of Alabama, have invented certain new and useful Improvements in Stone-Drilling Machines; and I do hereby declare the following to be a full, clear, and exact description of the invention, such as will enable others skilled in the art to which it pertains to make and use it, reference being had to the accompanying drawings, which form part of this specification.

My invention relates to an improvement in stone drilling machines; and the object of the same is to simplify the arrangement and improve the operation of a multiple drill, both in the manner of rotating the drills and applying the strikes thereto; and a further object is to provide an improved means for adjusting the machine to the work in hand.

The invention consists in the novel features of construction, and in the combination and arrangement of parts which will be fully described hereinafter and claimed, and illustrated in the accompanying drawings, in which—

Figure 1 is a side elevation of my improved machine. Fig. 2 is a vertical longitudinal sectional view of the same. Fig. 3 is a sectional plan view. Fig. 4 is an end view. Fig. 5 is a vertical cross sectional view. Figs. 6, 7, and 8 are detail views of the knocker, head K and drill respectively. Fig. 9 is a sectional view on line 9—9 of Fig. 1.

A is the outer frame of the machine constituting a vertical guideway for the inner drill carrying frame B. The respective frames are provided at their upper ends with cross bars a, b which are connected by vertical screw C for adjusting purposes. Journaled longitudinally in frame B is shaft D having gear d on one end which is engaged by propelling gear e carrying hand crank e'. On the shaft D are the beveled gears E which mesh with the correspondingly formed gears F fixed on short shafts G which have their inner bearings in cross bar H of frame B, and their outer bearings in arms h extending under shaft D as shown.

Bar H is formed with a series of vertical longitudinal recesses I in which the drills J

are located and through which the short shafts G extend. Each drill is provided with a head K having the radial serrations k on its under side which are adapted to be engaged by the double wiper L in recess I in bar H, and which is secured so as to revolve with shaft G. When the end of the knocker first engages the drill head it is near the center thereof but as the wiper continues to rise it is drawn therefrom and being in engagement with one of the radial serrations the drill is partially turned as will be readily understood, as well as being raised from the bottom of the cavity being drilled.

A series of hammers or strikes M is arranged over the drills, normally resting thereon, the same being secured to the outer ends of spring arms N which have their opposite ends secured to frame B. Each hammer has a projection m on its outer side for engagement with lifts O secured in regular succession to endless belts P, which latter at their lower ends encircle and are propelled by sprockets Q on shaft D, while the roller n is provided for their upper ends. The lifts are arranged on these belts so that the hammers are raised and fall with accuracy and regularity. Reservoir Q' is provided from which lead tubes Q'' for conveying water to the several drills.

For adjusting frame B automatically within frame A I provide the latter with the vertical racks R, one at each end. In the slotted ends of the bar H are the short shafts S, which are adapted to move therein longitudinally with relation to the said racks by means of arms T leading inward from the upper ends of said shafts and connected to the lever U on opposite sides of its pivotal point. These shafts carry worm gears V for engaging said racks, and beneath said gears are the beveled gears W which engage similar gears w on shaft D. Thus it will be seen that when worm gears W are in engagement with said racks they will lower the drilling mechanism automatically as the operation continues, thus keeping the drills constantly at their work. Screw C serves to raise frame B and may also be used for lowering the same when the worm gears are not in operation.

My preferred form of drill is shown in Fig.

8 and consists of a stem having the radial blades J' which are V-shaped as shown. A drill thus constructed is peculiarly adapted for stone work.

15 At each end of frame A are the slotted and longitudinally expanding legs X which diverge from a common securing point as shown and which are held in the desired adjustment, and from spreading by the cross brace 10 x. They are also connected to the frame side by the arm Y which holds the frame from oscillating. At the foot of each leg is a slotted weight Z for counteracting the tendency of the machine to vibrate.

15 The machine may be conveniently carried from place to place by handles z projecting from its four corners.

It will be observed that the knockers engage the drill heads just as the hammers are being raised, so that the two movements of the engaging parts do not clash.

Having thus fully described my invention, what I claim as new, and desire to secure by Letters Patent, is—

25 1. An improved drilling machine comprising a frame, a bar arranged therein having a series of longitudinal slots, wipers pivoted within the slots, drills movable vertically through the bar, heads carried by the drills 30 having radial serrations on their under sides which are adapted to be engaged by the wipers,

and means for rotating said shafts, and a strike mechanism for the drills, substantially as shown and described.

2. The combination of a fixed frame, a drill carrying frame movable therein, drills and a means for operating them, racks on the fixed frame, shafts carried by the movable frame which are adjustable toward the racks, worm gears on the shafts for engaging the racks, a 35 means for rotating the shafts, bars extending inward from the respective shafts, and a lever to which the said bars are secured to opposite sides of its pivotal point, substantially as shown and described. 45

3. The combination of shafts D, gears w thereon, oppositely beveled gears W, shafts S having the worm gears thereon, beveled gears on the lower ends of said shafts, each of said beveled gears engaging one of the gears 50 W, and racks R engaged by the worm gears, substantially as shown and described.

4. A drilling machine provided with diverging legs X, cross bar x, brace arm Y, and weights Z, substantially as shown and described. 55

In testimony whereof I affix my signature in presence of two witnesses.

JAMES EVRET RACHIELLES.
